UNITED STATES PATENT OFFICE.

EPPA H. RYON, OF PASADENA, CALIFORNIA, ASSIGNOR TO CROMPTON & KNOWLES LOOM WORKS, OF WORCESTER, MASSACHUSETTS, A CORPORATION OF MASSACHUSETTS.

TERRY-PILE-FABRIC LOOM.

Application filed November 6, 1924. Serial No. 748,252.

This invention relates to looms for weaving terry pile fabrics and an object of the invention is to provide a loom of this type wherein the pile forming mechanism is of very substantial construction and is moved toward and from pile forming position positively.

In the formation of terry pile fabrics the loom is provided with two warp beams, one to supply the ground warp which forms the body of the fabric and the other to supply the pile yarn, the latter beam being periodically released to permit the pile yarn to move lengthwise with respect to the ground warp. It is customary to lay two or more picks of filling a short distance behind the fell of the cloth and then to give the accumulated picks an additional forward motion at which time said picks grip the loose pile warp and move the same forward with respect to the ground warp, the pile warp bending transversely of the plane of the fabric to form loops.

My present invention relates more particularly to mechanism suited to the formation of high terry pile, and in the motion set forth herein I employ an eccentric somewhat similar to that shown in the Davidson Patent #936,310 but actuated positively in both directions by a sliding rack driven by mechanism very similar to a box motion.

It is a more particular object of my invention to employ a box motion for the purpose of moving the lay to form pile, the box motion being of a usual and well known form and so adapted that the operation of the boxes is not in the least disturbed by the addition of the means to form the pile.

With these and other objects in view which will appear as the description proceeds, my invention resides in the combination and arrangement of parts hereinafter described and set forth in the claims.

In the accompanying drawings wherein I have shown my invention as applied to one particular form of box motion,

Fig. 1 is a side elevation of a portion of a loom having my invention applied thereto and showing the lay in the extreme forward position which it occupies at the time of forming pile,

Fig. 2 is a horizontal section on line 2-2 of Fig. 1,

Fig. 3 is a fragmentary detailed view showing the connector and lay with the latter shown in forward position when laying the picks prior to pile formation, and

Fig. 4 is a section on line 4-4 of Fig. 1 looking in the direction of the arrows,

Fig. 5 is a horizontal section on reduced scale on line 5-5 of Fig. 1.

In carrying out my invention I provide a box motion which is capable of operating two boxes more than are to be operated with the terry forming mechanism, and in the form illustrated in the drawings I have shown a motion for four boxes connected to operate two boxes, the remainder of the box motion being used to operate the terry mechanism.

The loom frame 10 has journaled therein crank shaft 11 and bottom shaft 12 which are connected by suitable gearing (not shown) to cause the same to rotate in opposite directions. Fixed to shaft 11 is a gear 13 which meshes with an equal gear 14 secured to bevel gear 15, said gear 14 and bevel 15 being loosely mounted on stud 16. A second bevel gear 17 meshes with the first named bevel and is secured to an upright shaft 18 the upper end of which carries worm 19 placed to engage worm gear 20 rigid with chain cylinder 21. A lever 22 is suitably pivoted as at 23 to a fixed stud and has the outer end thereof attached to a connector 24 which extends downwardly.

Secured to bottom shaft 12 is a segment 25 which makes a complete revolution every second pick and cooperates with pinion 26 to move the latter about stud 27. A disc 28 is rigid with the pinion 26 and has a pivotal connection with the lower end of link 29 the upper end of which is connected as at 30 to the box lever 31 pivoted at 32. A lever 33 is pivoted to the stand 34 bolted or otherwise secured to box motion frame 35 and said lever has a horizontal arm 36 which may be connected to a lever (not shown) controlled by the pattern chain 37. A depending arm 38 engages a sliding member 39 which moves longitudinally of the shaft 27 to bring one of two diametrically opposite lugs 40 and 41, respectively, in the path of segment 25. When said segment engages one of the lugs, shaft 27 will be given a semi-rotation and link 29 will be

moved either to raise or lower stud 42 which has connection (not shown) with the boxes B.

In carrying out my improvements I make use of the lever 50 usually found on a box motion of the type shown herein, said lever being pivoted on stud 50' and having horizontal arm 51 which is attached to the lower end of connector 24 and having also a depending arm 52 having a finger which extends within groove 53 of slide 54 which is mounted on shaft 55. Pinion 56 is keyed or otherwise secured to shaft 55 and is provided with opposite slots to receive the parallel arms 57 and 58, respectively, said arms having lugs 59 and 60, respectively, which lie on opposite sides of shaft 55 and rotate in spaced planes so that only one of them is in line with the teeth of the pinion at a time.

Fixed to the inner end of shaft 55 is a disc 61 carrying a stud 62 which affords pivotal connection for the upper end of the link 63. The lower end of said link is pivotally connected to a lever 64 pivoted at 65 to a fixed stud and having a forwardly extending arm 66 slotted as at 67. A stand 68 is bolted to the loom side and has journaled therein a shaft 69 which extends across the loom, said shaft having fastened thereto a lever 70 having a stud 71 which extends through slot 67. The shaft 69 has secured thereto spaced levers 72 which lie adjacent the loom side and one of which is shown in Fig. 1. Each of the levers 72 is pivotally connected to the lower end of a lifter rod 73 the upper end of which is pivotally connected to a rack 74 see Fig. 5. Each lay sword has bolted thereto a guide 75 from which extend a pair of spaced ears 76 (see Fig. 4) between which the rack 74 moves, said guide having a tongue 77 on which said rack slides. The rack meshes with a gear 78 which has formed therewith eccentric 79 lying between the pinion and one of the ears 76. The said gear 78 and eccentric 79 rotate on stud 80 which extends through ears 76. The crank shaft 11 is provided with a crank 81 which is attached to connector 82 the forward end of which has pivotal connection with the eccentric. Guide 75 is bolted or otherwise secured to the lay sword and as the gear 78 is rotated the position of the stud 80 will change with respect to the crank 81 and thereby effect also a change in the position of the lay.

In order to actuate pinion 56 I secure to the bottom shaft 12 a pair of segments 83 and 84 which rotate in the same plane as the pinion 56. In the usual operation of a box loom the shuttle boxes will begin to move when the lay is about at bottom center and will finish their movement when the lay is approximately at top center, the boxes being approximately half through their mo-

tion at front center. Inasmuch as the terry forming mechanism must operate to throw the lay to its extreme forward position at front center it is necessary to advance said segments 83 and 84 so that they will be in position to actuate the pinion 56 somewhat earlier than would be the case if said pinion were functioning to control the position of boxes.

The disc 61 has lugs 86 and 87, respectively, which extend on opposite sides of the shaft. Stand 88 which is bolted to frame 35 and affords a mounting for lever 50 has extending forwardly therefrom a stud 89 on which is pivoted a lock lever 90 having spaced feet 91 and 92 which cooperate with lugs 86 and 87, respectively, to hold the pinion 56 and link 63 in position. Spring 93 serves to hold the feet against the lugs and permit the lock lever to be raised as the shaft 55 is rotated. In this way the rack is locked in its upper and lower positions.

Assuming that the loom is weaving a heading or border, the lay will need to be in extreme forward position and the eccentric will be in the position shown in Fig. 1, the slide 74 being down and the link 63 raised. The lever 22 and connector 24 will be in raised position so that the slide 54 is in inner position with lug 59 out of alignment 95 with the segments 83 and 84. This relative position of the parts will continue so long as the heading is being woven but when it is desired to change to pile fabric the lever 22 will be lowered, the result of which will be to move lug 59 into the path of one or the other of the segments 83 or 84 and as the segments continue to rotate the pinion 56 will be given a half revolution which will result in lowering the link 63 positively and a corresponding upward movement of rack 74 to move the lay to the position shown in Fig. 3. The pinion 78 will receive a half rotation and the stud 80 will be on the opposite side of the eccentric from that shown 100 in Fig. 1. The result of this is to shorten the distance between the lay and the crank shaft so that the reed will not move to the fell of the cloth on the next beat up. As the next segment approaches pinion 56 on the 105 next pick it will find lug 60 out of its path and will pass without acting to rotate said pinion.

If a three pick terry is being woven, the parts will remain in this position until two 120 picks have been laid with the lay in its rearward range of motion. During the laying of the third pick, however, the lever 22 will be raised by the pattern chain 37 and lug 60 will be moved into the path of the rotating 125 segments and as these latter continue to rotate one of them will engage said lug 60 and pinion 56 will be rotated a half revolution. The result of this last motion will be to raise link 63 and move the parts to the 130

position shown in Fig. 1 so that the picks previously laid slightly behind the fell of the cloth can be beaten to extreme forward position to form pile. I have chosen herein 5 to show my invention applied to the weaving of so-called three pick terry and for that reason it is necessary to have a roll R on every third bar of that part of the chain which corresponds to the pile section of the 10 fabric but it will be readily understood that I am not limited to this particular type of weave since a roll R could be placed on every fourth bar should it be desired to weave four pick terry. It will be understood 15 that there is a rack 74 and eccentric 79 on each lay sword.

From the foregoing it will be seen that I have provided a terry forming mechanism of very substantial construction sufficiently 20 strong to stand all strains incident to the beating up of the pile and that I have provided for moving the eccentric which positions the lay positively in both directions and that the eccentric is furthermore locked 25 in extreme positions. The lay is relatively heavy and cannot be depended upon to return to its rearward range of action under influence of a spring such as shown in the aforesaid Davidson patent, but the motion 30 set forth herein insures the proper placing of the lay when in either range of action. Furthermore I have made use of a standard type of box motion to accomplish these results.

35 Having thus described my invention it will be apparent that changes and modifications may be made therein by those skilled in the art without departing from the spirit and scope of the invention and I do not wish 40 to be limited to the details herein disclosed, but—

What I claim is:

1. In a loom, a crank shaft, a lay, eccentric connections between the lay and shaft to 45 vary the relative position of the lay and shaft, and controlling means for said eccentric connections to actuate the latter positively in two directions, said means including a rack slidable on the lay in a direction 50 transverse to the motion of the lay.

2. In a loom, a crank shaft, a lay, a connector for the crank shaft, an eccentric between the connector and the lay, and means to move the eccentric positively in both 55 directions, said means including a rack slid- able on the lay in a direction transverse to the motion of the lay.

3. In a loom, a crank shaft, a connector 60 therefor, a lay, an eccentric located between the connector and the lay, means movable to two positions to move the eccentric positively in opposite directions, and additional means to lock said eccentric moving means when in either position.

65 4. In a loom, a crank shaft, a connector

therefor, a lay, a sword therefor, an eccentric interposed between the connector and the lay, means to rotate the eccentric including a rack slidable longitudinally along the lay sword, and means to actuate said rack.

70

5. In a loom, a crank shaft, a connector therefor, a lay, a sword therefor, an eccentric interposed between the connector and the lay, means to rotate the eccentric including a rack slidable on the lay sword, and 75 means to actuate said rack positively in both directions.

75

6. In a loom, a crank shaft, a connector therefor, a lay, a sword therefor, an eccentric interposed between the connector and the lay, means to rotate the eccentric including a rack slidable on the lay sword, means to actuate said rack positively in both directions, and mechanism to lock said means in 80 both positions.

85

7. In a loom, a crank shaft, a connector therefor, a lay, an eccentric interposed between the connector and the lay, a bottom shaft, a rotating member secured to the bottom shaft, and connections between the rotating member on the bottom shaft and the eccentric to move the latter by said rotating member, said connections including a rack slidable relatively to the lay, a pinion connected to the eccentric and meshing with the 90 rack, and connections between the rack and the rotating member to move the rack positively in opposite directions as said member rotates.

90

8. In a loom, a crank shaft, a connector 100 therefor, a lay, an eccentric interposed between the connector and the lay to vary the position of the lay with respect to the connector, a bottom shaft, a segment gear fixed to the bottom shaft, a pinion adapted to be 105 rotated by said segment, and connections between the pinion and the eccentric to move the latter as the pinion rotates.

105

9. In a loom, a crank shaft, a lay, an eccentric located between the crank shaft and 110 the lay to vary the position of the lay with respect to the crank shaft when said eccentric is rotated, a bottom shaft, a toothed segment thereon, a pinion, connections between the pinion and the eccentric to cause the latter to rotate as the pinion rotates, and pattern controlled mechanism to connect the pinion to the segment as the latter rotates to cause rotation of said pinion.

115

10. In a loom, a crank shaft, a lay, an eccentric interposed between the crank shaft and the lay to vary the position of the latter with respect to the crank shaft as said eccentric is rotated, a bottom shaft, a toothed segment fastened thereto and rotating therewith, a pinion, a crank rotatable with said pinion, and connections between the crank and the eccentric to cause the latter to rotate as the pinion rotates the crank.

120

11. In a loom, a crank shaft, a lay, an ec- 130

centric located between the crank shaft and the lay to vary the position of the lay with respect to the crank shaft when said eccentric is rotated, a bottom shaft, a toothed segment carried thereby, a pinion adapted to be rotated by said segment, pattern controlled mechanism to establish operative driving connection between the segment and the pinion, a crank rigid with the pinion, a lever 10 operatively connected to the crank at one end thereof, and means operated by the other end of the lever to rotate the eccentric when said lever is moved by the crank.

12. In a loom of the class described, a 15 crank shaft, a bottom shaft, geared connec-

tions between said shafts, a lay, devices on said lay effective to change the position of said lay with respect to said crank shaft, shifting shuttle boxes, a segmental gear fast on said bottom shaft, mechanism arranged 20 to be driven by said segmental gear, a second mechanism arranged to be driven by said segmental gear, pattern surfaces to control both of said mechanisms, connections from said first named mechanism to said shifting 25 shuttle boxes, and connections from said second mechanism to said devices.

In testimony whereof I have hereunto affixed my signature.

EPPA H. RYON.
